UNITED STATES PATENT OFFICE

163,978

PRINTED FABRIC OR THE LIKE

Elizabeth N. Timmons, Portland, Oreg., assignor to Jantzen Knitting Mills Inc., Portland, Oreg.,
a corporation of Nevada

Application September 25, 1950, Serial No. 12,341

Term of patent 3½ years

(Cl. D92—1)

To all whom it may concern:

Be it known that I, Elizabeth N. Timmons, a citizen of the United States of America, residing at Portland, county of Multnomah, State of Oregon, have invented a new, original, and ornamental Design for a Printed Fabric or the Like, of which the following is a specification, reference being had to the accompanying drawing, forming a part hereof.

The figure is a face view of a full width of a printed fabric showing my new design. The design unit is outlined by dot and dash lines and is repeated as indicated.

I claim:

The ornamental design for a printed fabric or the like, substantially as illustrated and described.

ELIZABETH N. TIMMONS.
